UNITED STATES PATENT OFFICE.

BERNT M. JOHNSON, OF RACINE, WISCONSIN.

HORSE-COLLAR FASTENER.

SPECIFICATION forming part of Letters Patent No. 357,831, dated February 15, 1887.

Application filed November 6, 1886. Serial No. 218,126. (No model.)

To all whom it may concern:

Be it known that I, BERNT M. JOHNSON, of Racine, in the county of Racine, and in the State of Wisconsin, have invented certain new and useful Improvements in Horse-Collar Fasteners; and I do hereby declare that the following is a full, clear, and exact description thereof.

My invention relates to fasteners for horse-collars and hames; and it consists in certain peculiarities of construction, as will be hereinafter described with reference to the accompanying drawings, and subsequently claimed.

In the drawings, Figure 1 represents a perspective view of the sections that form my fastener, showing the same disunited; Fig. 2, a perspective view of one of the sections with the latch-plate removed; Fig. 3, an under side view of the latch-plate, and Fig. 4 a vertical transverse section of the parts in their united position.

Referring by letter to the drawings, A, B represent two metallic sections that are designed to be respectively secured in any suitable manner to the lower ends of horse-collar sections and constitute a fastening therefor.

The section A of my fastener has its face provided with an opening, a, and an ear, b, the latter being rounded at its end and cut away at c to engage a latch-plate, C, pivotally connected to said face. In order that the latch-plate C may be flush with the face of the fastener-section A, I offset this face and seat said latch-plate therein. The point marked d on the flange e, formed by offsetting the fastener-section A, serves as a stop to limit the movement of the latch-plate.

A spring, D, is arranged on a stud, f, in the offset part of the fastener-section A, and fits the respective recesses g h in said section and under side of the latch-plate. The spring D exerts its force to cause an automatic return of the latch-plate to its normal position when the same has been lifted by its thumb-piece i to disunite the sections, and also after this latch-plate has been automatically raised during the operation of coupling said sections, as will be hereinafter more fully described.

The section B of the fastener has its face provided with an opening, a', and an ear, b', these parts being oppositely arranged with relation

to the corresponding parts, a b, on the face of the section A, and the ear b' is also rounded at its end and cut away to engage the latch-plate C.

The fastener-section A is provided with a staple, E, that serves to hold the martingale-strap of a harness, and this staple consists of two metallic straight strips, m, cast in the metal that composes said section, as shown by Fig. 2, and then bent to meet one another, as illustrated in Fig. 1.

In the operation of my invention, when the fastener-sections are brought together, the ear on the face of one passes through the opening in the face of the other, and, as the latch-plate C in its normal position partially closes the opening a in the section A, the rounded end of the ear b' serves to automatically raise this plate to allow said ear to enter this last-named opening. When the faces of the sections come flush together, the spring D will automatically actuate the latch-plate to come into the cut-away portions of the ears b b', thus forming a lock to hold said sections in their united position.

Having thus fully described my invention, what I claim as new, and desire to secure by Letters Patent, is—

1. A fastener for horse-collars, consisting of two suitable metallic sections having their faces provided with oppositely-arranged openings and ears, the latter being cut away to form seats, and a latch-plate pivotally connected to one of the sections to engage the seats in the ears, substantially as and for the purpose set forth.

2. A fastener for horse-collars, consisting of two suitable metallic sections having their faces provided with oppositely-arranged openings and ears, the latter being cut away to form seats, a latch-plate pivotally connected to one of the sections to engage the seats in the ears, and a spring arranged to hold said latch-plate in its normal position, substantially as and for the purpose set forth.

3. A fastener for horse-collars, consisting of two suitable metallic sections having their faces provided with oppositely-arranged openings and ears, the latter being cut away to form seats, one of the sections having its face offset, a latch-plate pivoted in the offset to be

flush with the non-offset portion of said face and engage the seats in the ears, substantially as and for the purpose set forth.

4. A fastener for horse-collars, consisting of two suitable metallic sections having their faces provided with oppositely-arranged openings and ears, the latter being cutaway to form seats, a latch-plate pivotally connected to one of the sections to engage the seats in the ears, and a stop to limit the movement of the latch-plate.

5. A fastener for horse-collars, consisting of two suitable metallic sections, means, substan-

tially as described, for coupling these sections, and one thereof provided with a staple that consists of two straight metallic pieces cast with this latter section and bent to meet one another, as and for the purpose set forth.

In testimony that I claim the foregoing I have hereunto set my hand, at Racine, in the county of Racine and State of Wisconsin, in the presence of two witnesses.

BERNT M. JOHNSON.
